COIL HOLDER

Alvin L. Winkler, Chicago, Ill., assignor to Acme
Steel Company, Chicago, Ill., a corporation of
Illinois

Application November 9, 1950, Serial No. 194,855

9 Claims. (Cl. 242—124)

1

This invention relates to improvements in coil holders and its purpose is to provide a novel device for holding a coil of metal, such as steel strapping, wire and the like, during the operation of withdrawing the coiled material for use.

Holders for metal coils have heretofore been provided with removable side plates to permit coils of material to be placed upon the rotatable hubs of the holders but these devices have not been entirely satisfactory for the reason that they have not been capable of accommodating coils of different axial widths. The width of coils of metal strapping and the like may vary slightly due to irregularities in winding and there may be much greater variations in the widths of the coils placed on a holder due to the presence or absence of side disks of fiberboard or the like which sometimes form parts of the coil units. This variation has made it necessary at times to use different coil holders for coils of material of the same width and gauge.

The principal object of the present invention is to provide an improved coil holder which is adjustable to accommodate coils of different axial widths. Another object of the invention is to provide a coil holder having side plates which are relatively adjustable in their spaced relation to receive metal coils of varying widths, in combination with means for readily and accurately securing them in adjusted relation. Still another object of the invention is to provide a coil holder having two side plates, one of which is capable of being readily secured in any one of a plurality of predetermined positions spaced from the other side plate. Another object is to provide improved means for detachably securing a side plate on the hub of a coil holder. Other objects relate to various features of construction and arrangement which will appear more fully hereinafter.

The nature of the invention will be understood from the following specification taken with the accompanying drawings in which one embodiment of the invention, and modification of a portion thereof, are illustrated. In the drawings,

Figure 1 shows an edge elevation of a coil holder embodying the features of the present invention with the hub of the holder mounted upon a movable truck;

Fig. 2 shows an edge elevation of the hub portions of the coil holder illustrated in Fig. 1 when they are separated from each other;

Fig. 3 shows a vertical section taken transversely of the outer portion of the hub of the coil holder illustrated in Fig. 1 illustrating the relative positions of the parts after the outer side

2

plate has been moved into interlocking engagement with the hub of the holder;

Fig. 4 is a sectional view similar to that of Fig. 3 illustrating the relative positions of the parts preliminary to effecting a relative rotation of the two side plates to effect the interlocking connection between the outer side plate and the hub which is illustrated in Fig. 3;

Fig. 5 shows an axial section taken on the line 5—5 of Fig. 3;

Fig. 6 shows an axial section taken on the line 6—6 of Fig. 4;

Fig. 7 shows a perspective view of the outer end portion of the hub of the holder illustrating the slots of different lengths which are engaged by a locking pin; and

Fig. 8 shows an end elevation of a modified form of hub having an increased number of slots for effecting a greater variation in the spaced relation of the side plates of the holder.

As illustrated in Fig. 1, the improved coil holder 10 is shown as being mounted upon a truck or carriage 11 having supporting wheels 12 and a foot 13 which are adapted to rest upon a floor or other support 14. The truck 11 has an upstanding frame 15 provided with a handle 15a and with a transverse frame member 16 on which the coil holder 10 is rotatably supported. The holder 10 may, of course, be otherwise mounted and it is ordinarily provided with a brake for controlling the rotation of the holder during the withdrawal of strip material or wire therefrom.

The coil holder 10 comprises a hollow hub or drum 18 which is adapted to receive a coil 19 formed of steel strapping, round wire, or other material, usually formed of metal, which is wound in a coil and which is placed upon the hub or drum 18 for the purpose of permitting the coiled material to be gradually withdrawn for use. The coil 19 may include side disks 20 formed of non-metallic material, such as fiberboard or the like, and these disks are usually attached to the metal coil to form a unit which is slipped on to the hub or drum 18 of the coil holder. This drum or hub has attached thereto or formed integrally therewith an inner circular side plate 21 against which the coil is adapted to seat and the hub or drum also carries an outer side plate 22 which is detachably mounted upon the hub or drum so that it may be withdrawn to permit the coil of material, with or without side plates, to be slipped on to the hub in the position which is shown particularly in Figs. 5 and 6.

The frame member 16 is provided with an enlarged boss 24 in which there is mounted a

stationary shaft or spindle 25 arranged to project laterally from the member 16. The hub or drum 18 has an inner cylindrical cavity 18a which receives the spindle 25 and two ball bearing units 26 are mounted between the spindle 25 and the bore of the hub or drum 18 so that the drum is freely rotatable about a horizontal axis. The two ball bearing units 26 are spaced apart by a sleeve 27 which fits over the spindle 25 and the ball bearing unit 26 at the outer end of the spindle 25 is retained in position against the sleeve 27 by means of a locking ring 28 which detachably engages an annular groove formed in the spindle 25. The other ball bearing unit is held by the sleeve 27 against the end face of the boss 24 and it is retained in position with respect to the sleeve 27 by means of a locking ring 29 which bears against the end face of the ball bearing unit and interlocks with an annular groove formed in the outer wall of the bore 18a of the drum. In this way the drum 18 is held securely against axial displacement with respect to the supporting spindle 25 about which it revolves.

The outer end of the hub or drum 18 is reduced in diameter to form a cylindrical axial projection 18b which fits into the axial bore 22b of the hub portion 22a of the outer side plate 22. This side plate is adapted to be secured in the innermost position shown in Figs. 3 and 5 wherein the inner surface of this side plate bears against the outermost surface of the coil of material which is mounted upon the drum. For the purpose of securing the hub portion 22a of the outer side plate on the part 18b of the drum, there is provided a locking device comprising a rod 30 which is mounted to reciprocate in a cylindrical bore 18c formed in the part 18b of the drum. This rod has secured in the outer end thereof a transversely extending pin 31 which is adapted to engage either one of two transversely extending slots 32 and 33 which are formed in the outer end of the part 18b of the drum to extend axially inward from the end face of the part 18b, as shown particularly in Fig. 7. The pin 31 extends inwardly into the cavity 18a of the drum 18 and into a central bore 25a which extends inwardly from the outer end of the spindle 25. A coil spring 35 is mounted on the rod 30 within the bore 25a and bears at its inner end against a collar 36 which is secured on the rod 30 by a pin 37. The outer end of the spring 35 bears against a collar 38 which seats against the end face of the cavity 18a of the drum. With this arrangement, the spring 35 tends normally to move the rod 30 inwardly and to hold the locking pin 31 in engagement with one or the other of the transverse slots 32 and 33. The slot 33 is greater in depth than the slot 32 so that when the pin 31 occupies the slot 33 the outer side plate 22 may be moved inwardly to engage a coil of material of relatively narrow width such as one which is not provided with the side disks 29. When the side disks are present or if the coil is of unusual axial width for any other reason, the locking pin 31 may engage the slot 32 of lesser depth so that the outer side plate 22 may be spaced farther from the inner side plate 21. The cavity 22c in the hub portion is normally closed by a cap 41 which is detachably held in place by spring fingers 48 frictionally engaging the annular wall of the cavity.

For the purpose of holding the pin 31 in engagement with the selected slot of the part 18b

and to retain the hub portion 22a of the outer side plate in position on the hub or drum 18, there is provided a circular locking plate 40 which seats on the end wall 22d in the cylindrical cavity 22c formed in the outer end of the hub 22a of the outer side plate. This plate 40 is secured to this hub portion 22a by means of two studs 41 which are located diametrically opposite to each other as illustrated in Figs. 3 and 4. The locking plate 40 is formed of hard steel or the like, to serve as a wear plate on the end of the hub, and it is provided with two arcuate inwardly inclined tongues 40a which extend partially around the axial bore 22b and seat against corresponding inwardly inclined surfaces 22e which are formed by recesses in the end wall 22d of the cavity 22c. At the free ends of the tongues 40a, the locking plate is provided with openings or notches 40b which register with longitudinal grooves 22f formed in the hub portion 22b to receive the projecting ends of the locking pin 31 when this hub portion is passed into telescoping engagement with the projection 18b of the drum, as shown in Figs. 4 and 6.

During the process of assembly, the openings 40b and the registering grooves 22f are aligned with the locking pin 31 and the outer side plate 22 is thrust onto the part 18b of the drum, thus causing the ends of the pin to pass through the openings 40b and slots 22f until the parts are in the relative positions shown in Figs. 4 and 6. The outer side plate is then rotated in a counterclockwise direction, thereby causing the pin 31 to be thrust outwardly against the compression of the spring 35 as its end portions ride over the inclined cam surfaces formed by the tongues 40a. This camming action insures the location of the side plate 22 in the desired position determined by the slots 32 or 33 which are selected for engagement by the locking pin, and the rotation of the side plate is continued until the hub portion 22a reaches the position wherein further rotation is arrested by the engagement of the ends of the locking pin with the studs 41. As this condition is approached, the ends of the locking pin 31 ride over small projections 40c which are formed in the plate 40 to extend axially outward so that when the pin 31 reaches the final position shown in Figs. 3 and 5, relative reverse rotation of the side plates is prevented by the coaction of the projections 40c with the pin. It will be understood that the pin 31 and the rod 30 are resiliently held by the spring 35 during this operation of assembly so that some yielding of the rod 30 is permitted, but the spring 35 should be of sufficient strength to maintain the locking engagement of the pin 31 with the projections 40c during the normal use of the holder in effecting the withdrawal of coiled material therefrom.

When a coil of material on the drum 18 has been consumed and it is desired to remove the outer plate 22 of the holder to permit a new coil to be placed in position on the drum, this may be done by effecting a relative movement of the two plates 21 and 22 in the reverse direction, whereupon the pin 31 will move outwardly to a sufficient extent, as permitted by the spring 35, to allow the ends of the pin 31 to ride over the projections 40c, whereupon the tongues 40a may be moved to a position wherein the pin 31 again registers with the openings 40b so that the outer plate 22 and its hub 22a may be withdrawn from engagement with the portion 18b of the hub or

In assembling the device, the pin 31 may, of course, be rotated with the rod 30 until it registers with the desired slot 32 or 33 so that when the pin is moved inwardly to the inner end of the slot by the action of the spring 35, the side plate 22 will be in engagement with the outer face of the particular coil of material which is then on the drum 18. If it be desired to construct the holder for use with coils of material varying widely in axial widths, a greater number of transverse slots might be formed in the outer end of the portion 18b of the hub or drum 18, as shown in Fig. 8 where the outer end of a hub portion 44b, corresponding to the part 18b, is provided with four transverse slots 45, 46, 47 and 48 which have different depths measured endwise of the hub portion.

Although one embodiment of the invention and a modification of a portion thereof have been shown and described by way of illustration, it will be understood that the invention may be constructed in various other forms which come within the scope of the appended claims.

I claim:

1. A coil holder for metal coils comprising, a drum, a side plate having a hub portion mounted on said drum, a locking member carried by said drum and arranged to occupy different positions axially thereof, and means for interlocking said hub portion with said member in each of said positions of said member.

2. A coil holder for metal coils comprising, a drum, a side plate having a hub portion mounted on said drum, a locking member carried by said drum and arranged to occupy different positions axially thereof, and means operated by rotation of said hub portion on said drum for interlocking said hub portion with said member in each of said positions of said member.

3. A coil holder for metal coils comprising, a rotatable drum, a side plate having a hub portion mounted on said drum, said drum being provided with transverse slots of different depth extending inwardly from the outer end thereof, a locking device carried by said drum and including a pin adapted to engage a selected one of said slots, and means for interlocking said hub portion with said pin to hold said hub portion on said drum.

4. A coil holder for metal coils comprising, a rotatable drum, a side plate having a hub portion mounted on said drum, said drum being provided with transverse slots of different depth extending inwardly from the outer end thereof, a locking device carried by said drum and including a pin adapted to engage a selected one of said slots, resilient means tending to hold said pin in engagement with the selected slot, and means for interlocking said hub portion with said pin to hold said hub portion on said drum.

5. A coil holder for metal coils comprising, a rotatable drum, a side plate having a hub portion mounted on said drum, said drum being provided with transverse slots of different depth extending inwardly from the outer end thereof, a locking device carried by said drum and including a pin adapted to engage a selected one of said slots, and a locking plate attached to said hub portion and having a tongue adapted

6 to interlock with said pin upon rotation of said hub portion on said drum.

6. A coil holder for metal coils comprising, a rotatable drum, a side plate having a hub portion mounted on said drum, said drum being provided with transverse slots of different depth extending inwardly from the outer end thereof, a locking device carried by said drum and including a pin adapted to engage a selected one of said slots, resilient means tending to hold said pin in engagement with the selected slot, and a locking plate attached to said hub portion and having a tongue adapted to interlock with said pin upon rotation of said hub portion on said drum.

7. A coil holder for metal coils comprising, a rotatable drum, a side plate having a hub portion mounted on said drum, said drum being provided with transverse slots of different depth extending inwardly from the outer end thereof, a locking device carried by said drum and including a pin adapted to engage a selected one of said slots, resilient means tending to hold said pin in engagement with the selected slot, and a locking plate attached to said hub portion and having a tongue adapted to interlock with said pin upon rotation of said hub portion on said drum, said hub portion and said locking plate having openings to receive the ends of said pin.

8. A coil holder for metal coils comprising, a rotatable drum, a side plate having a hub portion mounted on said drum, said drum being provided with transverse slots of different depth extending inwardly from the outer end thereof, said drum having a reduced tubular extension at its outer end, a rod slidably mounted in said extension, a transverse locking pin carried by the end of said rod and adapted to engage a selected one of said slots, a spring mounted on said rod within said drum for retracting said rod to cause said pin to move to the bottom of the selected slot, said pin projecting transversely beyond said extension, and a locking plate secured to said hub portion and having arcuate tongues adapted to interlock with said pin.

9. A coil holder for metal coils comprising, a rotatable drum, a side plate having a hub portion mounted on said drum, said drum being provided with transverse slots of different depth extending inwardly from the outer end thereof, said drum having a reduced tubular extension at its outer end, a rod slidably mounted in said extension, a transverse locking pin carried by the end of said rod and adapted to engage a selected one of said slots, a spring mounted on said rod within said drum for retracting said rod to cause said pin to move to the bottom of the selected slot, said pin projecting transversely beyond said extension, a locking plate secured to said hub portion and having arcuate tongues adapted to interlock with said pin, and means for normally limiting the relative rotation of said drum and said hub portion.

ALVIN L. WINKLER.
